(57) **CLAIM**

We claim the ornamental design for a twirling baton with four bladed ball and tip, as shown and described.

DESCRIPTION

FIG. 1 is a perspective view of the twirling baton with four bladed ball and tip shown partially broken away for the ease of illustration.

FIG. 2 is an elevation view seen from the larger (ball) end of FIGS. 1 and 4;

FIG. 3 is an elevation view seen from the smaller (tip) end of FIGS. 1-3; and,

FIG. 4 is a plan view of FIGS. 1-3, the opposite side and both 90° rotations being identical to the view shown.
